UNITED STATES PATENT OFFICE.

ALLEN F. COULTER, OF GIRARD, ALABAMA.

BUNCH BUILDER FOR SPINNING MACHINES.

Application filed May 13, 1927. Serial No. 191,115.

This invention relates to a bunch builder for spinning machines, and has for its object to wind the yarn in a more substantial and level manner at the lower portion of the bobbin, than that obtained by bunch builders now in general use, to materially reduce, when weaving, yarn waste thereby resulting in a saving in yarn costs.

10 A further object of the invention is to provide, in a manner as hereinafter set forth, a bunch builder for winding the yarn on the lower portion of the bobbin in a manner to overcome the objection when weaving of the yarn or thread overlapping and falling over, which results in entanglement of the yarn and waste of that portion of the yarn on the lower part of the bobbin.

A further object of the invention is to provide, in a manner as hereinafter set forth, 20 a bunch builder for winding the yarn on the lower portion of the bobbin to prevent retardation of the weaving operation and further whereby the yarn or thread will be carried across the cloth, when weaving, to a 25 greater extend than that obtained by bunch builders now in general use, under such conditions providing for a material reduction in waste and a substantial saving to the manufacturer.

30 Further objects of the invention are to provide, in a manner as hereinafter set forth, a bunch builder for spinning machines which is simple in its construction and arrangement, strong, durable, compact, thoroughly efficient in its use, readily installed, and comparatively inexpensive to set up.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

50 Figure 1 is a side elevation of a bunch builder in accordance with this invention and with the mechanism in active position with respect to a pair of ring rails of a spinning machine.

55 Figure 2 is a view similar to Figure 1 with the mechanism in inactive position.

Figure 3 is a top plan view of a bunch builder in accordance with this invention.

Figure 4 is a fragmentary view in section and upon an enlarged scale of the bunch builder.

Figure 5 is a side elevation of the release element for the shifting element for the actuator.

Figure 6 is an elevation of the actuator. 65

Figure 6 is an elevation of the actuator. 63
A bunch builder mechanism in accordance with this invention is common to a pair of ring rails 7, 8 of a spinning machine which are arranged in parallelism and substantially spaced from each other. Each rail has 70 connected therewith a set of spaced spindles as indicated at 9. The rails 7, 8 are synchronously shifted in a vertical direction or rather upwardly against the action of a counterweighting means therefor which provides for the rails to move downwardly after reaching the limit of their upward movements. The rails are intermittently shifted in an upward direction. 75

The reference character 10 indicates an inverted yoke-shaped member forming a part of the spinning frame and having the arms thereof indicated at 11, 12 connected together by a cross piece 13. Journaled in the arms 11, 12, below the cross piece 13 is a rock shaft 14 formed with a crank arm 15 carrying a counterweight 16. The crank arm 15 is positioned between the transverse center and one end of the rock shaft 14. Projecting from the rock shaft 14 in proximity to each end thereof is a crank arm which are indicated at 17, 18. The arms 17, 18 extend in an opposite direction with respect to the arm 15. The arms 17, 18 are arranged inwardly with respect to the side arms of the yoke 10. The arms 17, 18 are pivotally connected at their free ends, as at 19 to a vertically disposed link 20. One of the links is pivotally connected to the rail 7 and the other of the links is pivotally connected to the rail 8. Fixed to the rock shaft 14 and extended therefrom in a direction

shaft 14 and extended therefrom in a direction opposite with respect to the direction of the arm 15 is a rocker member therefor which consists of an elongated bar 21 provided at its free end with a cylindrical head 22 of substantial length and of a diameter greater than the width of the bar or rod 21. The rocker member is of greater length than either of the crank arms 17 or 18. An actuator element associates with the rocker arm and which in connection with the counter-

weight 16 provides for an up and down movement simultaneously of the rails 7, 8 during the bunching operation.

Arranged in spaced relation with respect to the yoke 10, as well as disposed substantially centrally with respect thereto, is a vertical support 23 and which in connection with the cross piece 13 supports a rotatable operating shaft 24 for the actuating element for the rocker member. The actuating element will be presently referred to. The shaft 24 in proximity to the support 23 carries a gear wheel 25 which meshes with a driving gear 26 therefor. The gear 26 is carried by a shaft 27, which is journaled in the support 23, and operated by a prime mover not shown. The shaft 24 is a prolongation of the shaft 24 shown in Patent 1,556,814 and carries the usual builder cam. With reference to Figure 4 the shaft 24 has its top formed with a key way of appropriate length and at one end of the key way 28, there is secured to the shaft 24, by a pin 29 a stop collar 30. Bodily carried by the shaft 24, so as to rotate therewith, is a sleeve 31 having its periphery formed throughout with a worm thread, as indicated at 32. The sleeve 31 is bodily shifted lengthwise of the shaft 24 in one direction, by a controlling spring 33. The sleeve 31 is coupled to the shaft 24 by a key 34 which is fixed to the sleeve 31 and projects from one end thereof and slides in the key way 28. The collar 30 opposes one end of the sleeve 31 and abutting against the other end of the sleeve 31 is the hub 35 of a cam in the form of a circular disk 36 having a fluted or corrugated edge to provide alternately disposed grooves 37 and lobes 38. The grooves 37 are of greater length than the lobes 38. The hub 35 is fixedly secured to the key 34 and the disk 36 is bodily shifted with the sleeve 31 and shaft 24. The shaft 24 provides the actuating element for intermittently rocking or shifting the rock member which is carried by the rock shaft 14. The shaft 24 at a point spaced from the other end of the key way 28 has secured therewith, by the pin 39, a collar 40 and interposed between the latter and the disk 36 is the controlling spring 33. The spring 33 normally tends to shift the disk 36 and sleeve 31 in a direction towards the collar 30. The sleeve 31 and disk 36 is shifted against the action of the spring 33 by a shifting element to be presently referred to. The disk 36 travels from end to end of the head 22 and on the rotation of the disk, when travelling from end to end of the head 22, it will intermittently rock the rod or bar 21, under such conditions actuating the rock shaft 14 against the action of its counterweight 16. The disk 36 travels from that end of the head which is integral with the rod or bar 21 to the other end of the head and then

passes thereoff. When the disk 36 passes off of the head 22, it will oppose the free end of the head and will be in the position as shown in Figure 2. By lifting the weight 16, the head 22 is lowered and the spring 33 will shift the disk 36 towards the collar 30 to a position above the head 22, then on release of the weight 16 the head 22 will be brought into engagement with the edge of the disk 36. 75

Mounted on the shaft 24, at a point between the collar 30 and the cross piece 13 is a collar 41, having pivots 42 for a releasing element for the shifting element of the sleeve 31. The shifting element for the sleeve 31 will be presently referred to. The releasing element comprises a yoke 43 having its arms mounted on the pivot 42 and which are angularly disposed with respect to the shaft 24. Depending from the yoke 43 at one side of the center of the base 44 thereof is a vertical arm 45 having extended from its lower end a right angularly disposed projection 46 which is arranged below the rod or bar 21 of the rocker member. 90 The arms of the yoke 43 extend towards the collar 30.

Arranged over the shaft 24, is the shifting element for the sleeve 31, and which consists of a bar 47 pivotally connected at one end, 95 as at 48, to the inner side of the cross piece 13 and at a point above the shaft 24. The bar 47, at a point between its transverse median and its forward end carries a depending yoke 49 which straddles the shaft 100 24 and pivotally connected to the sides of the yoke 49 are the free ends of the arms of the yoke 43. The bar 47 extends over the sleeve 31 and is formed with a defending tapered nose 50 which seats in the threaded 105 periphery 32 of the sleeve 31. The pivots between the yoke 43 and the yoke 49 are indicated at 51.

The engagement of the nose 50 in the threaded periphery 32 of the sleeve 31 will 110 provide for the shifting of the sleeve 31 in a direction towards the collar 40 during the operation of the shaft 24, and as the sleeve 31 moves in such direction the disk 36 will be carried therewith. The movement of the 115 sleeve 31 and disk 36 in a direction towards the collar 40 will be had against the action of the spring 33. The initial position of the elements of the builder is as shown in Figure 1 and the nose 50 will be arranged in close 120 proximity to the hub 35. As the shaft 24 rotates, the sleeve 31 and disk 36 will be carried in a like direction and owing to the construction of the edge of the disk 36, such edge shifting the head 22, the rock 125 member will be intermittently shifted downwardly to impart a rocking movement to the shaft 14, which in turn will elevate the rails 7, 8 against the action of the counterweight 16. When the grooves 37 oppose the heads 130

22, the weight 16 will provide for the elevating of the rails 7, 8. As the disk 36 rotates with respect to the head 22, it will also travel from end to end thereof, until the 5 disk 36 passes off of the head 22 to the position shown in Figure 2. When the disk 36 passes off the head 22, the control of the traverse is returned to the usual builder cam on shaft 24 of the patent referred to. At 10 the completion of the winding operation the operator will lift the weight 16 and the spring 33 will then cause the disk 36 to assume the position shown in Figure 1. When 15 the weight 16 is elevated by the operator, the rod or bar 21 will engage the end 46 of the arm 45, rocking the release element on its pivot in a direction whereby the yoke 43 will be elevated carrying the shifting element therewith, so that the nose 50 will be 20 moved clear of the threaded periphery of the sleeve 31, under such conditions the spring 33 can operate in a manner to shift the disk 36 and sleeve 31 towards the collar 30.

The builder is attached to the spinning 25 frame and is connected to the ring rails for the purpose of producing an upward and downward motion in winding the thread around the bobbin. The bobbin, of course, remains stationary and after being wound 30 is removed from the spinning frame.

The operation of the bunch builder, in a manner as stated, will cause the threads to wind on the base of the bobbin in the form of a figure 8, that is to say in the form of 35 a pair of oppositely extending loops connected together, and such windings will be in a substantial and level manner, so that in weaving, the yarn or threads may be carried across the cloth in a manner to prevent it from becoming entangled or to prevent 40 an overlapping or falling over thereof, which results in entanglement and by overcoming the latter objection, it will provide for a material reduction in waste and a substantial 45 saving to the manufacturer, therefore it is thought the many advantages of a bunch builder, in accordance with this invention, can be readily understood, and although the preferred embodiment of the invention is as illustrated and described, yet it is to be understood that the changes in 50 the details of construction can be had which will fall within the scope of the invention as claimed.

55 What I claim is:

1. In a bunch builder for spinning machines a counter-balanced rock shaft provided with a rocker member, a rotatable, spring

controlled means riding against and travelling off said member for actuating it to 60 intermittently rock said shaft in one direction during successive thread winding periods against the action of its counterbalance, means for connecting said shaft to a spindle carrying rail for vertically moving the latter 65 on the actuation of said shaft, releasable means engaging with said rotatable means for imparting a sliding action or pull to cause it to travel over and off and rock said 70 member.

2. In a bunch builder for spinning machines a counterbalanced rock shaft provided with a rocker member, a rotatable, spring controlled means impacting against and travelling on and off said member for actuating it to intermittently rock said shaft in one direction during successive thread winding periods against the action of its counterbalance, means for connecting said shaft to a spindle carrying rail for vertically moving 75 the latter on the actuation of said shaft, releasable means engaging with said rotatable means for imparting a sliding action thereto to cause it to travel over and rock said member, and means engaged by the rocker member for releasing the means which provides for the sliding of said rotatable means. 80

3. In a bunch builder for spinning machines, a spindle rail shifting mechanism including a rocker element, an actuating mechanism including a spring controlled 90 rotatable cam device engaging with said elements for intermittently rocking it in one direction to provide for the operation of said shifting mechanism, and means engaging in 95 said actuating mechanism to cause said cam device during the rotation thereof to slide over said element and then off the latter.

4. In a bunch builder for spinning machines, a spindle rail shifting mechanism including a rocker element, an actuating mechanism including a spring controlled 100 rotatable cam device engaging with said elements for intermittently rocking it in one direction to provide for the operation of said shifting mechanism, and means engaging in 105 said actuating mechanism to cause said cam device during the rotation thereof to slide over said element and then off the latter, and a releasable element operated 110 from said rocker element for said means after said cam device has been moved off said rocker element.

In testimony whereof, I affix my signature herewith.

ALLEN F. COULTER.
